UNITED STATES PATENT OFFICE.

LEWIS E. DICKINSON, OF BOONTON, NEW JERSEY, ASSIGNOR TO WESTERN ELECTRIC COMPANY, INCORPORATED, OF NEW YORK, N. Y., A CORPORATION OF NEW YORK.

PROTECTIVE DEVICE FOR ELECTRIC CIRCUITS.

1,252,412.

Specification of Letters Patent.

Patented Jan. 8, 1918.

Application filed November 6, 1916. Serial No. 129,767.

To all whom it may concern:

Be it known that I, LEWIS EDMUND DICKINSON, a citizen of the United States, residing at Boonton, in the county of Morris and State of New Jersey, have invented 5 certain new and useful Improvements in Protective Devices for Electric Circuits, of which the following is a full, clear, concise, and exact description.

10 This invention relates to protective devices for electric circuits, and more particularly to heat coils for the protection of telephone apparatus against abnormal currents, which, although not of sufficient value 15 to operate the fuses, would, if allowed to flow, result in injury to the apparatus.

In the type of heat coils commonly used, it is the general practice to employ a metal pin as a switching member, this pin being 20 fastened to a metal sleeve by means of low fusing solder, which is, softened through the medium of heat generated by abnormal currents which flow through the heating element. In still other types, parts of the 25 heat coils are soldered directly to the mounting springs. However, in all of these types the parts joined by the low fusing solder are of relatively generous size, thereby requiring that a considerable amount of heat 30 be generated before these parts are raised to the temperature at which the solder becomes plastic. Not only is considerable heat taken up by these parts, due to their mass, but no provision is made for the heat insulation of these parts from the surrounding 35 metal parts of the device itself or the mounting springs which act as additional conducting and radiating surfaces. It therefore becomes necessary to generate an 40 amount of heat far in excess of that utilized for melting the solder, which in turn necessitates a heating element of high resistance.

The object of this invention is to provide 45 a heat coil which will not only be certain and reliable in its operation, but which will also be very efficient in operation, thereby making it possible to decrease the resistance of the heating element. Since this heating element is placed directly in the line circuit, it is highly important that its resistance 50 be kept as low as possible, especially in the case of heat coils to be used on long and expensive toll lines.

To attain these objects this invention consists of improvements whereby the heat

generated by the current flowing through the heating element is concentrated at a given point and very efficiently utilized in melting the fusible material, the softening of which allows the device to function and 60 protect the apparatus. This is accomplished by making the metal parts which are joined by the fusible metal small in mass, and heat-insulating these parts from the surrounding metal parts of the protective device and 65 its mountings.

The several features of this invention may be more readily understood by reference to the accompanying drawing in which there is shown a cross-sectional view of a 70 preferred type of heat coil, wherein 1 represents a pin of wood or other suitable heat-insulating material having a recessed portion in which a strip of metal foil 2 is wrapped and prick-punched to hold it in 75 place. Surrounding this portion of the pin is a thin metal tube or sleeve 3, preferably of copper, one end of which is flared out or flanged, as shown at 4, and a washer 5 of fiber or other non-heat-conducting material 80 is placed over this tube and against the flared-out portion. A second washer 6 of fiber or other non-heat-conducting material is placed against the flared-out end of the tube, and a metal band 7 is spun over 85 the washers to make them a unitary structure with the tube. This tube is then placed over the pin 1, and a drop of low melting solder 9 is inserted in the perforation 10 of the tube, which, when solidified, holds 90 the pin and tube rigidly together. A winding 11, preferably of a material having a high positive temperature coefficient, is placed over the tube 3, one end being first connected to the metal band 7. The assembled pin and tube are then placed within the shell 12 which is of bakelite or other insulating material, and into one end of which is crimped a metal cap 13. The end of the pin extends into the hollow hub 14 100 of the metal cap 13, and is rigidly fastened by means of a crimping or staking operation. The assembly of the heat coil is then completed by drawing the unfastened end of the winding through a slot in the shell 105 and soldering it to the cap 13.

As the method of inserting coils of the type in question in a protector strip is well understood in the art, being illustrated, for example, in Williams Patent No. 588,206 110

of August 17, 1897, it is thought to be unnecessary to illustrate the method in the present case.

In service the heat coil is under spring pressure, and in case the solder is softened by abnormal currents in winding 11, relative movement is permitted between the pin 1 and the sleeve 3, allowing said pin to project farther through the sleeve, and in so doing, to ground the line in the well-known manner as illustrated by the patent hereinbefore referred to. While the device shown is a preferred type, there are many modifications which might be made without in any way departing from the spirit of the invention. For example, under certain conditions, it might be preferable to employ a metal pin instead of one of wood or other similar material. Such a construction would be slightly less efficient than that shown, since it would increase the mass of metal in the device to be heated, but the construction nevertheless, would be such as to prevent any considerable amount of heat being conducted away to the mounting springs. Again, where a pin of insulating material is used, instead of wrapping a piece of metal foil in the recessed portion of the pin, it might be found preferable to resort to the use of a metal ring molded on the pin.

What is claimed is:

1. In a protective device for telephone circuits, a sleeve of heat-conducting material, a circuit - controlling element extending through said sleeve, heat-softenable material for mechanically joining said sleeve and said circuit-controlling element, a heat-generating element, terminals for said heat-generating element, and means for normally insulating said sleeve from said terminals.
2. In a protective device for telephone circuits, a sleeve of heat-conducting material, a circuit-controlling element of non-conducting material extending through said sleeve, heat-softenable material for mechanically joining said sleeve and said circuit-controlling element, a heat-generating element, terminals for said heat-generating element, and means for normally insulating said sleeve from said terminals.
3. In a protective device for telephone circuits, a sleeve of heat-conducting material, a circuit-controlling element of non-conducting material extending through said sleeve and provided with a metallic section for attachment to said sleeve, and heat-softenable material for mechanically joining said sleeve and said circuit-controlling element.
4. In a protective device for telephone

circuits, a sleeve of heat-conducting material, a circuit-controlling element of non-conducting material extending through said sleeve and provided with a metallic section for attachment to said sleeve, heat-softenable material for mechanically joining said sleeve and said circuit-controlling element, a heat-generating element, terminals for said heat-generating element, and means for insulating said sleeve from said terminals.

5. In a protective device for telephone circuits, a sleeve of heat-conducting material, a circuit-controlling element of non-conducting material extending through said sleeve and provided with a metallic section for attachment to said sleeve, heat-softenable material for mechanically joining said sleeve and said circuit-controlling element, a heat-generating element composed of material having a high positive temperature coefficient, terminals for said heat-generating element, and means for insulating said sleeve from said terminals.

6. In a protective device for telephone circuits, a shell of non-conducting material, a metal cap attached to one end of said shell, said cap being provided with a hollow hub into which extends a circuit-controlling element, a sleeve of heat-conducting material surrounding a portion of said circuit-controlling element, heat softenable material for mechanically joining said sleeve and said circuit - controlling element, a heat - generating element, terminals for said heat-generating element, and means for insulating said sleeve from said terminals.

7. In a protective device for telephone circuits, a shell of non-conducting material, a metal cap attached to one end of said shell, said cap being provided with a hollow hub, and a circuit-controlling element extending into said hub.

8. In a protective device for telephone circuits, a shell of non-conducting material, a metal cap attached to one end of said shell, said cap being provided with a hollow hub, and a circuit-controlling element of non-conducting material extending into said hub.

9. In a protective device for telephone circuits, a sleeve of heat-conducting material having an outward extending member on one end, a terminal band carried by said sleeve, and insulating means between said band and said sleeve.

In witness whereof I hereunto subscribe my name this 4th day of November, A. D. 1916.

LEWIS E. DICKINSON.
